Specification for Design.

Patented May 10, 1921.

Application filed October 27, 1920. Serial No. 420,030. Term of patent 14 years.

To all whom it may concern:

Be it known that I, WILLIAM A. BARTLEY, a citizen of the United States, and a resident of Washington, in the county of Warren and State of New Jersey, have invented a new, original, and ornamental Design for a Sectional Sash-Weight, of which the following is a specification, reference being had to the accompanying drawings, forming part thereof.

Figure 1 is a side elevation.

Fig. 2 is a front elevation.

Fig. 3 is a plan view of a sectional sash weight, showing my new design.

I claim:

The ornamental design for a sectional sash weight, as shown.

WILLIAM A. BARTLEY.
